[57] CLAIM

The ornamental design for a telephone handset, substantially as shown and described.

DESCRIPTION

FIG. 1 is a perspective view of a telephone handset showing our new design;

FIG. 2 is a top plan view thereof;

FIG. 3 is a bottom plan view thereof;

FIG. 4 is a side elevation view thereof, the opposite side being essentially a mirror image of the side shown; and

FIG. 5 is an end elevation view thereof, the opposite end being essentially the same.

FIG. 1

FIG. 2

FIG. 3

FIG. 4

FIG. 5
